DESIGN FOR A CONTAINER

Elmer C. Werner and Leo X. Burger, Delphos, Ohio, assignors to The New Delphos Manufacturing Company, Delphos, Ohio, a corporation of Ohio

Application October 1, 1934, Serial No. 53,452

Term of patent 7 years

To all whom it may concern:

Be it known that we, ELMER C. WERNER and LEO X. BURGER, citizens of the United States, and residents of Delphos, in the county of Allen, State of Ohio, have invented a new, original, and ornamental Design for a Container, of which the following is a specification, reference being had to the accompanying drawing, forming a part thereof.

Figure 1 is a side elevation of a container showing our design; Fig. 2 is a sectional view taken on the line 2—2 of Figure 1; and Fig. 3 is a top view.

The dominant features of our design consists of the balanced arrangement of peripheral beads at the upper and lower portions of the cylindrical part of the container, with the closely related slanting ribs disposed in the space between the beads.

We claim:

The ornamental design for a container, substantially as shown and described.

In testimony whereof we have hereunto signed our names to this specification.

ELMER C. WERNER.
LEO X. BURGER.
